UNITED STATES PATENT OFFICE.

WELLINGTON W. MUIR, OF LOCKPORT, NEW YORK.

PROCESS OF AND APPARATUS FOR OPERATING INTERNAL-COMBUSTION ENGINES.

Original application filed August 16, 1922, Serial No. 582,219. Divided and this application filed March 18, 1926. Serial No. 95,766.

This invention relates to a process of and an apparatus for operating internal combustion engines, and has for its object to provide a means which will be more efficient than those which have been heretofore proposed.

With these and other objects in view, the invention consists in the novel steps and combinations of steps constituting the process, and in the novel parts and combinations of parts constituting the apparatus, all as will be more fully hereinafter disclosed and particularly pointed out in the claims.

This application is a division of my co-pending application Serial No. 582,219, filed August 16, 1922 and entitled Process of and apparatus for operating internal combustion engines.

Referring to the accompanying drawing forming a part of this specification, in which like numerals designate like parts:

1 indicates an internal combustion engine jacket, 2 a pipe or passage leading from said jacket, 3 a Venturi tube, or what is commonly known as a Gifford injector, connected to 25 said tube 2, 40 a tank into which said injector delivers, 41 a filling opening or cap so disposed as to limit the level of the liquid as at 42 in the tank 40. The top of the tank 40 is provided with a pocket or any suitable 35 closed recess 39 extending above the top of said tank, and within said pocket is disposed the upper open end of a tube or passage 8 extending down through the tank 40 and connecting with the chamber 9 located below 50 said tank but above the water tubes 10 of any suitable form of radiator core, with which said chamber communicates. 11 indicates heat radiating fins or other means for conducting away the heat of the water in said 55 tubes 10; 12 indicates a liquid tank or chamber into which the lower ends of the tubes 10 open, and 13 indicates a vent tube or passage leading from the tank 12, adapted to carry away any air that may be brought over by 60 the condensed fluid in the tank 12 and provided at its upper end with any suitable valve construction such as indicated at 48 adapted to permit the escape of air from the system to the atmosphere and to prevent air 65 from entering the system.

Leading from the tank 12 is the pipe or passage 14 provided with a check valve 46, and further provided with a vertical extension 47 of said pipe 14 leading from said 70 check valve 46 to the venturi 3. Leading

from the lower portion of the tank 40 is the pipe or passage 43 leading in turn to the pump 44 which delivers the cooled liquid received therein through the passage 45 back into the jacket 1 of the engine.

In operation the pump 44 circulates liquid around and around the circuit through the jacket 1, passage 2, the Venturi tube 3, and the passages 43 and 45. Thus is the pressure in the jacket maintained at a point higher than that of the atmosphere, or than that in the tank 40. Steam is given off from the liquid level 42 upon increased engine temperatures, which passes down along with any air that may be entrapped in the fluid through 70 the pipe 8 into the chamber 9 through the water tubes 10 of the radiator 25 and finds itself condensed in the tank 12, from whence it is sucked by the Venturi tube or injector 3 past the valve 46 up through the tube 47 and is delivered into the passage 43 associated with the tank 40 all as clearly indicated in the drawing by which the liquid in the lower portion of the tank 40 and in the passage 43 is subjected to a cooling action. In the meantime, any air that has been entrapped in the fluid escapes from the tank 12 by passing up through the vent tube 13 and past the valve 48 into the atmosphere. The said valve 48 prevents air from entering the system when the pressure therein is less than that of the atmosphere, which is often the case when the steam is freely condensed. The funnel shaped mouth 50, at the upper extremity of the passage 43 where the same joins the tank 40, causes the fluid which is forced under pressure through the venturi 3 to escape or pass upwardly into the tank 40 as will be readily understood.

This escape for the water obviously makes possible an even flow of the fluid through the jacket and the maintaining of the pressure in the jacket at a substantially constant point notwithstanding the variations in temperature of the combustion chambers. In 100 this case, it will be observed that there is a considerable superatmospheric pressure always existing in the motor jacket and generally a pressure less than that of the atmosphere existing in the tank 12 at the bottom of the radiator.

It will now be clear that one is enabled to maintain a constant pressure in the jacket above that of the atmosphere, and therefore a substantially constant temperature 110

in the combustion chambers, which is higher than that due to an atmospheric pressure in the jacket, and from this fact follows two very important advantages in the operation 5 of the motor. That is, as is well known, it is very desirable indeed to maintain around the combustion chambers a substantially uniform temperature because the fuel mixture can be so adjusted as to ignite with greater 10 efficiency at a given temperature, and when this said temperature is once established the motor will continually run with its greatest satisfaction, so long as said temperature is maintained. But it is further well known 15 that it is very difficult indeed to maintain such uniform temperature because the temperature of the combustion chambers are constantly changing, due to the varying loads put on the engine and to the varying 20 operating conditions such as changes in the atmospheric temperature, changes in the altitude at which the motor is operated and therefore changes in the oxygen supply, etc. In this invention, on the other hand, the 25 temperature of the combustion chambers is raised considerably above that which could be maintained with an atmospheric pressure in the jacket, and therefore considerable variations in the temperature of the combustion 30 chambers can be had without varying appreciably over long periods the temperature of the jacket fluid, for the surplus heat given off by the combustion chambers under heavy loads will be absorbed in the form of 35 latent heat and carried off in the form of steam. On the other hand, when the temperature of the combustion chambers begins to lower due to lighter loads, the surplus heat that has already been absorbed by the 40 jacket walls, the steam present etc., will be given back to a greater or less extent and thus it is found to be rather difficult to suddenly change the jacket temperature or the 45 satisfactory performance of the motor, notwithstanding the sudden changes of load and working conditions.

Thus it will be seen that the pump 44 delivers the cooling fluid to the jacket 1 at a rate which is sufficient to build up a pressure of the fluid in the jacket greater than that of the atmosphere due to the restriction 3 in the cooling circuit. As the engine temperatures increase vapors will be condensed in the radiator, and the condensate collecting in the tank 12 will be returned to the cooling circuit by the action of the pressure built up in the jacket due to said pump and said restriction. That is to state, the pressure in the jacket will force the fluid through 50 the pipe 2 and through the restriction 3 therein in such manner as to create a low pressure in the tube 47 sufficient to draw the condensate from the tank 12 there-through and into the system.

It is obvious that those skilled in the art

may vary the details of construction as well as the arrangement of parts without departing from the spirit of the invention, and it is further recognized that like changes could be made in the operation of the system, without departing from the spirit of the invention as disclosed. Therefore I do not wish to be limited to the above disclosure except as may be required by the claims.

What is claimed is:

1. In a cooling system for internal combustion engines the combination of a jacket; a tank for holding an excess supply of cooling fluid for said jacket; means to continuously circulate said fluid through said tank and jacket; means for cooling a portion of the fluid from said tank; means for cooling the other portion of said fluid; a second tank for receiving the cooled fluid from said last named means; and means including a Venturi tube controlled by said circulating means for returning the cooled fluid to the circuit. 70

2. In a cooling system for internal combustion engines the combination of a jacket; a tank closed to the atmosphere for holding an excess supply of cooling fluid for said jacket; means to continuously circulate said fluid through said tank and jacket; means for cooling a portion of the fluid from said tank; means for cooling the other portion of said fluid; a second tank for receiving the cooled fluid from said last named means; means associated with said second tank to permit the egress of the air entrained in said circuit; and means including a Venturi tube controlled by said circulating means for returning the cooled fluid to the circuit. 90

3. In a cooling system for internal combustion engines the combination of a jacket; a tank closed to the atmosphere for holding an excess supply of cooling fluid for said jacket; means to continuously circulate said fluid through said tank and jacket; means for cooling a portion of the fluid from said tank; means for cooling the other portion of said fluid; a second tank for receiving the cooled fluid from said last named means; means associated with said second tank to permit the egress of the air entrained in said circuit while preventing the ingress of air thereto; and venturi means controlled by said circulating means for returning the cooled fluid to the circuit. 100

4. In a cooling system for internal combustion engines the combination of a jacket; a tank for holding an excess supply of cooling fluid for said jacket said tank adapted to limit the amount of fluid in said system; means to continuously circulate said fluid through said tank and jacket; means for cooling a portion of the fluid from said tank; means comprising a downflow radiator for cooling the other portion of the fluid from said tank; a second tank for re- 110

- ceiving the cooled fluid from said last named means; and means comprising a Venturi tube controlled by said circulating means for returning the cooled fluid to the circuit.
5. In a cooling system for internal combustion engines the combination of a jacket; a tank for holding an excess supply of cooling fluid for said jacket; means to continuously circulate said fluid through said tank and jacket; means for cooling a portion of the fluid from said tank; means for cooling the other portion of said fluid; a second tank vented to the atmosphere for receiving the cooled fluid from said last named means; and means for returning the cooled fluid to the circuit at a point above said vent.
6. In a cooling system for internal combustion engines the combination of a jacket; a tank for holding an excess supply of cooling fluid for said jacket; means to continuously circulate said fluid at a relatively high pressure through said tank and jacket; means for cooling a portion of the fluid from said tank; means for cooling the other portion of the fluid from said tank; a second tank disposed below said first named tank and vented to the atmosphere for receiving the cooled fluid from said last named means; and valved and restricted means controlled by said circulating means for returning the cooled fluid under relatively low pressure to the circuit at a point above said vent.
7. In a cooling system for an internal combustion engine provided with a jacket for a cooling fluid and a tank, the combination of means to circulate said fluid through said jacket and said tank; means to maintain a pressure in said jacket higher than in said tank; and means for condensing the vapors liberated in said tank and returning the condensate in a crossflow direction to said circuit by the action of the pressure created by said last named means.
45. 8. In a cooling system for an internal combustion engine the combination of a jacket; a tank for holding an excess supply of cooling fluid for said jacket; a pump and circuit for continuously circulating said fluid through said jacket and tank; a Venturi tube in said circuit to restrict the flow of fluid and maintain the pressure in said jacket above that in said tank; a radiator provided with an upper chamber; a tank for condensed fluid associated with said radiator; means to pass vapors from said first named tank into said upper chamber and radiator for condensation and collection in said second named tank; and means comprising a tube connected to said Venturi tube to pass the condensate from said second named tank back into said circuit.
60. 9. The process of maintaining a temperature in the jacket fluid of an internal combustion engine cooling circuit higher than that corresponding to atmospheric pressure which consists in so restricting the passage of said fluid out of said jacket as to cause it to rise to a superatmospheric pressure; causing the condensed portion of said fluid after being cooled to be returned to said circuit by the action of the pressure created by the restricted flow; and continuously forcing the fluid of said circuit back into said jacket at a rate sufficient to maintain said last named pressure.
10. The process of maintaining in the cooling circuit of an internal combustion engine, while the same is running, a temperature in the jacket fluid higher than that corresponding to its boiling point at atmospheric pressure which consists in condensing the vapors evolved while creating and maintaining a superatmospheric pressure in said jacket; and causing the condensate to be returned to said circuit by the action of said pressure.
11. The process of maintaining in the cooling circuit of an internal combustion engine, while the same is running, a temperature in the jacket fluid higher than that corresponding to its boiling point at atmospheric pressure which consists in creating and maintaining a superatmospheric pressure in said jacket while circulating said fluid and creating vapors therefrom; and causing said pressure to return to said circuit the vapors in condensed form, whereby said fluid will be preserved.
12. In a cooling system for internal combustion engines a continuous circuit for the liquid including a jacket and means for separating the vapor from the liquid, a condenser associated with the circuit to receive the vapor and means connected therewith to return the condensate to the circuit by the pressure created in said jacket, and a vent to the atmosphere in direct communication with said condensate.
13. In a cooling system for internal combustion engines a continuous circuit for the liquid including a jacket and means for separating the vapor from the liquid as well as means to develop a pressure in said jacket, a condenser associated with the circuit to receive the vapor, and a connection between said condenser and said last named means for the return of the condensate to said circuit, whereby said return is controlled by said pressure.
14. In a cooling system for internal combustion engines provided with a jacket, a continuous circuit for the liquid including means adapted to create a pressure in said jacket, and means associated with said circuit for receiving and condensing vapors therefrom, and returning the condensate to said circuit by the action of the pressure created in said jacket.
65. 15. In a cooling system for internal com-

bustion engines provided with a continuous circuit for the liquid including a jacket and means for separating the vapor from the liquid, means to develop a pressure in said jacket sufficient to return to said circuit the condensed vapors from a condenser associated therewith.

16. In a cooling system for internal combustion engines provided with a jacket, a

continuous circuit for the liquid including 10 means adapted to create a pressure in said jacket, and means associated with said circuit for receiving and condensing vapors therefrom, said first named means further adapted to return the condensate to said 15 circuit under the action of said pressure.

In testimony whereof I affix my signature.

WELLINGTON W. MUIR.
